US00D713931S

(12) **United States Design Patent**
Dobias et al.

(10) **Patent No.:** **US D713,931 S**
(b4) **Date of Patent:** ** Sep. 23, 2014

(54) **SPRAYER**

- (71) Applicant: **Central Garden & Pet Company**,
Walnut Creek, CA (US)
- (72) Inventors: **Scott F. Dobias**, Johns Creek, GA (US);
Antonio Gatta, Philadelphia, PA (US);
Christopher Murray, Philadelphia, PA (US); **Christopher Phelan**,
Collingswood, NJ (US); **David Schiff**,
Highland Park, NJ (US); **Mathieu Zastawny**, Philadelphia, PA (US)
- (73) Assignee: **Central Garden & Pet Company**,
Walnut Creek, CA (US)

(**) Term: **14 Years**(21) Appl. No.: **29/445,683**(22) Filed: **Feb. 14, 2013****Related U.S. Application Data**

- (63) Continuation-in-part of application No. 13/737,593,
filed on Jan. 9, 2013.
- (51) **LOC (10) Cl.** **23-01**
- (52) **U.S. Cl.**
USPC **D23/213**
- (58) **Field of Classification Search**
USPC D23/213, 223, 225, 226; 239/302, 308,
239/310, 332, 333, 337, 526; 222/465.1,
222/383.1, 383.3, 143, 154; D8/1, 2

CLAIM

The ornamental design for a sprayer, as shown and described.

DESCRIPTION

FIG. 1 is a front pictorial view of a sprayer in a first configuration, in accordance with a first embodiment of the invention;

FIG. 2 is a rear pictorial view of the sprayer of FIG. 1 in the first configuration;
FIG. 3 is a front elevation view of the sprayer of FIG. 1 in the first configuration;
FIG. 4 is a rear elevation view of the sprayer of FIG. 1 in the first configuration;
FIG. 5 is a left elevation view of the sprayer of FIG. 1 in the first configuration;
FIG. 6 is a right elevation view of the sprayer of FIG. 1 in the first configuration;
FIG. 7 is a top plan view of the sprayer of FIG. 1 in the first configuration;
FIG. 8 is a bottom plan view of the sprayer of FIG. 1 in the first configuration;
FIG. 9 is a front pictorial view of the sprayer of FIG. 1 in a second configuration;
FIG. 10 is a rear pictorial view of the sprayer of FIG. 1 in the second configuration;
FIG. 11 is a front elevation view of the sprayer of FIG. 1 in the second configuration;
FIG. 12 is a rear elevation view of the sprayer of FIG. 1 in the second configuration;
FIG. 13 is a left elevation view of the sprayer of FIG. 1 in the second configuration;
FIG. 14 is a right elevation view of the sprayer of FIG. 1 in the second configuration;
FIG. 15 is a top plan view of the sprayer of FIG. 1 in the second configuration;
FIG. 16 is a bottom plan view of the sprayer of FIG. 1 in the second configuration;
FIG. 17 is a front pictorial view of a sprayer in a first configuration, in accordance with a second embodiment of the invention;

FIG. 18 is a rear pictorial view of the sprayer of FIG. 17 in the first configuration;
FIG. 19 is a front elevation view of the sprayer of FIG. 17 in the first configuration;
FIG. 20 is a rear elevation view of the sprayer of FIG. 17 in the first configuration;
FIG. 21 is a left elevation view of the sprayer of FIG. 17 in the first configuration;
FIG. 22 is a right elevation view of the sprayer of FIG. 17 in the first configuration;
FIG. 23 is a top plan view of the sprayer of FIG. 17 in the first configuration;
FIG. 24 is a bottom plan view of the sprayer of FIG. 17 in the first configuration;
FIG. 25 is a front pictorial view of the sprayer of FIG. 17 in a second configuration;
FIG. 26 is a rear pictorial view of the sprayer of FIG. 17 in the second configuration;
FIG. 27 is a front elevation view of the sprayer of FIG. 17 in the second configuration;
FIG. 28 is a rear elevation view of the sprayer of FIG. 17 in the second configuration;
FIG. 29 is a left elevation view of the sprayer of FIG. 17 in the second configuration;
FIG. 30 is a right elevation view of the sprayer of FIG. 17 in the second configuration;
FIG. 31 is a top plan view of the sprayer of FIG. 17 in the second configuration; and,
FIG. 32 is a bottom plan view of the sprayer of FIG. 17 in the second configuration.
The broken line showing is included for the purpose of illustrating and forms no part of the claimed design.
